UNITED STATES PATENT OFFICE.

PERRY WESTOVER, OF CLYMER, PENNSYLVANIA.

SIGNAL.

1,276,464.

Specification of Letters Patent. Patented Aug. 20, 1918.

Application filed July 5, 1917. Serial No. 178,763.

To all whom it may concern:

Be it known that I, PERRY WESTOVER, a citizen of the United States, residing at Clymer, in the county of Indiana and State 5 of Pennsylvania, have invented certain new and useful Improvements in Signals, of which the following is a specification, reference being had to the accompanying drawings.

10 This invention relates to certain improvements in signals and has relation more particularly to a device of this general character especially designed and adapted for use in connection with railways; and it is an 15 object of the invention to provide a novel and improved signal wherein the same is caused to operate by the rolling stock.

It is also an object of the invention to provide a device of this general character of 20 an electric type and wherein the operating circuit is under control of a plurality of circuit closers adapted to be operated by the rolling stock for causing the requisite operation of the signal and wherein certain of the 25 closers so cooperate that after one train has passed thereover the same are so adjusted as to assure the requisite operation of the signal upon the passing of a second train in the same direction.

30 The invention consists in the details of construction and in the combination and arrangement of the several parts of my improved signal whereby certain important advantages are attained and the device is 35 rendered simpler, less expensive and otherwise more convenient and advantageous for use, all as will be hereinafter more fully set forth.

The novel features of the invention will 40 hereinafter be definitely claimed.

In order that my invention may be the better understood, I will now proceed to describe the same with reference to the accompanying drawings, wherein—

45 Figure 1 is a view in top plan of a signal constructed in accordance with an embodiment of my invention with the top plate of the housing omitted;

50 Fig. 2 is a longitudinal vertical sectional view taken through the housing as disclosed in Fig. 1;

Fig. 3 is a sectional view taken substantially on the line 3—3 of Fig. 1;

Fig. 4 is a sectional view taken substantially on the line 4—4 of Fig. 1. 55

Fig. 5 is a sectional view taken substantially on the line 5—5 of Fig. 1;

Fig. 6 is a sectional view taken substantially on the line 6—6 of Fig. 4; and

Fig. 7 is a diagrammatic view illustrating 60 my invention as herein embodied.

As disclosed in the accompanying drawings, H denotes a housing of predetermined configuration and dimensions and positioned to one side of and in close proximity to a rail R comprised in a track structure, and the side or vertical wall of the housing H next to the rail R is provided with a plurality of longitudinally spaced and vertically directed slots 1. Through each of the 70 slots 1 is disposed an arm 2 having its outer end pivotally engaged with the vertically arranged post 3 mounted for sliding movement in the bracket 4 carried by the housing H. 75

The upper end of the post 3 is provided with the elongated shoe S which is adapted to be engaged by the wheels of a train to depress the same.

The arm 2 is pivotally mounted intermediate its length, as at 5, with the standard 6 positioned within the housing H and the inner end of said arm 2 is pivotally engaged, as at 7, with an extremity of the bell lever 8. The opposite extremity of each of the 85 bell levers 8 coacting with two adjacent shoes has pivotally engaged therewith the arm or link 9 which is pivotally engaged with the blade B of a circuit closer. 80

As herein disclosed, the circuit closers are 90 two in number and are identified as C and C¹.

The stationary contact 10 of the inner circuit closer C is electrically connected through the medium of the conductors a 95 with the source of electrical energy E herein set forth as dry cells arranged within the housing H at the opposite ends thereof. Leading from the source of electrical energy E to the signal G is the conductor b. Leading from the signal G and in electrical connection with the stationary contact 11 of the second or end circuit closer C¹ is the conductor c. The blades B of the closers C and C¹ are electrically connected by the conductor g. 100 105

The blade B of the inner closer C is constantly urged in a direction away from its coacting stationary contact 10 through the medium of the retractile member 15, herein disclosed as a conventional coil spring, which is interposed between the inner end portion of the adjacent arm 2 and the bottom of the housing H.

Presuming a train to be traveling in the direction as indicated by the arrow in Fig. 1, it will be perceived that the shoe S coacting with the circuit closer C¹ will be depressed resulting the blade B of said circuit closer C¹ contacting with the stationary contact 11 of said circuit closer C¹. When the shoe S of the circuit closer C is depressed it will be at once self-evident that the contact of the blade B of said circuit closer C with the stationary contact 10 there- 20 of will result in a closing of a circuit which will cause the signal G, which is of a gong type, to sound. It will also be at once appreciated that the member 15 will serve to automatically break the contact between the blade B and the stationary contact 10 of the circuit closer C whereby the signal G will be caused to intermittently operate as a train is passing over the shoes S.

16 denotes an arm positioned within and disposed longitudinally of the housing H and pivotally engaged at substantially its longitudinal center with the standard 17 within the housing H. The arm 16 is of such length as to terminate below the inner end 35 of the arm 2 coacting with the circuit closer C and the arm 2 of the shoe S adjacent to the closer C¹. The extremities of the arm 16 are pivotally engaged, as at 18, with the under faces or edges of said arms. Through 40 the medium of the arm 16 it will be at once self-evident that upon the depression of one of the end shoes S the opposite end shoe will be elevated. It will also be at once self-evident that after a train has 45 passed over the several shoes S the shoe S coacting with the closer C¹ will be left elevated so that the signal G may be caused to operate by the passing of a train following.

From the foregoing description, it is 50 thought to be obvious that a signal constructed in accordance with my invention is of an extremely simple and comparatively inexpensive nature and is particularly well adapted for use by reason of the convenience 55 and facility with which it may be assembled, and it will also be obvious that my invention is susceptible of some change and modification without material departure from the principles and spirit thereof and for this 60 reason I do not wish to be understood as limiting myself to the precise arrangement and formation of the several parts herein shown in carrying out my invention in practice, except as hereinafter claimed.

I claim:

1. In combination with an electric signal and an operating circuit therefor, two circuit closers interposed in said circuit, one of said closers being positively operated into either open or closed position, the second circuit closer being positively operated into closed position, and means coacting with the second closer for automatically adjusting the same into open position independently of the first closer member. 75

2. In combination with an electric signal and an operating circuit therefor, two circuit closers interposed in said circuit, each of said closers including a stationary contact and a movable contact, a rock lever operatively engaged with each of the movable contacts, means coacting with each of the levers for moving the movable contact into closed position, and means coacting with one of the levers for maintaining the coacting movable contact normally in open position. 80

3. In combination with an electric signal and an operating circuit therefor, two circuit closers interposed in said circuit, each of said closers including a stationary contact and a movable contact, a rock lever operatively engaged with each of the movable contacts, means coacting with each of the levers for moving the movable contact into closed position, means coacting with one of the levers for maintaining the coacting movable contact normally in open position, and additional means coacting with the lever of the second movable contact for adjusting said second movable contact into open position. 90

4. In combination with an electric signal and an operating circuit therefor, two circuit closers interposed in said circuit, each of said closers including a stationary contact and a movable contact, a rock lever operatively engaged with each of the movable contacts, means coacting with each of the levers for moving the movable contact into closed position, means coacting with one of the levers for maintaining the coacting movable contact normally in open position, a third rock lever, means for imparting movement thereto, and an operative connection between the second and third levers where- 105 by the second lever is caused to adjust the coacting movable contact coacting therewith into open position upon movement of the third rock lever in one direction. 115

5. In combination with an electric signal 120 and an operating circuit therefor, two circuit closers interposed in said circuit, each of said closers including a stationary contact and a movable contact, a rock lever operatively engaged with each of the movable contacts, means coacting with each of the levers for moving the movable contact into closed position, means coacting with one 125

of the levers for maintaining the coacting movable contact normally in open position, a third rock lever, means for imparting movement thereto, and an operative connection between the second and third levers whereby said levers are caused to travel in opposite directions.

In testimony whereof I hereunto affix my signature in the presence of two witnesses.

PERRY WESTOVER.
